US0D1028986S

(12) **United States Design Patent** (10) **Patent No.:** **US D1,028,986 S**
(45) **Date of Patent:** **** May 28, 2024**

(54) **COMPUTING INPUT DEVICE**

(71) Applicant: **Microsoft Corporation**, Redmond, WA (US)

(72) Inventors: **John Helmes**, Limburg (NL); **Aditha May Adams**, Seattle, WA (US); **Simon Cameron Dearsley**, Bellevue, WA (US); **Go Osaki**, Shenzhen (CN); **Hongshan Sun**, Shenzhen (CN)

(73) Assignee: **Microsoft Corporation**, Redmond, WA (US)

(**) Term: **15 Years**

(21) Appl. No.: **29/837,968**

(22) Filed: **May 10, 2022**

(51) LOC (14) Cl. **21-01**

(52) U.S. Cl.

USPC **D14/412**; D21/333

(58) **Field of Classification Search**

USPC D14/218, 356, 383, 388, 391, 396, 398, D14/400, 401, 405, 406, 412, 413, 414, D14/415, 420, 426, 427, 407; D21/324,

D21/325, 329, 331, 332, 333; D13/168 CPC A63F 13/00; A63F 13/24; A63F 13/92; A63F 13/98; G06F 3/011; G06F 3/014; G06F 3/017; G06F 3/033; G06F 3/0338

(57) **CLAIM**

The ornamental design for a computing input device, as shown and described.

DESCRIPTION

FIG. 1 is a front perspective view of a computing input device showing our new design;

FIG. 2 is a bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The even length broken lines depict portions of the computing input device that form no part of the claimed design. The uneven length broken lines represent an unclaimed boundary of the claim and form no part of the claimed design.

1 Claim, 8 Drawing Sheets
